F. A. SCHIERBERG.

CAR REGISTER.

APPLICATION FILED AUG. 18, 1905.

UNITED STATES PATENT OFFICE.

FREDERICK A. SCHIERBERG, OF ST. LOUIS, MISSOURI.

CAR-REGISTER.

No. 818,563.

Specification of Letters Patent.

Patented April 24, 1906.

Application filed August 18, 1905. Serial No. 274,804.

To all whom it may concern:

Be it known that I, FREDERICK A. SCHIERBERG, a citizen of the United States, and a resident of St. Louis, Missouri, have invented 5 certain new and useful Improvements in Car-Registers, of which the following is a specification.

My invention relates to improvements in car-registers; and it consists of the novel 10 features hereinafter described and claimed.

This invention is an improvement over my Letters Patent No. 784,595, dated March 14, 1905.

The object of my invention is to provide a 15 register on a railway road-bed and place a recording mechanism on the car which, when both are brought in contact, will register the number of each car passing over the register. By such a device the officials can locate and 20 determine the destination of each car.

In the drawings, Figure 1 is a side elevation of a portion of the car-track, showing the recording mechanism applied thereto and the register located on the road-bed. Fig. 2 is a 25 top plan view of the same. Fig. 3 is a side view of the recording mechanism detached from the car. Fig. 4 is a side elevation of the register with the cover in section. Fig. 5 is a 30 right-hand end view of the register with the cover in section. Fig. 6 is a top plan view of the same with cover removed. Fig. 7 is a vertical sectional view of the register, taken through the center. Fig. 8 is a vertical cross-sectional view of the same, taken through the 35 center. Fig. 9 is a detail vertical sectional view of the recording mechanism, showing its construction. Fig. 10 is a detail perspective view of the combined register-raising and lid-operating mechanism.

Referring to the drawings in detail; 40 indicates an ordinary truck of a railway-car, on which is mounted an arm 12, its one end provided with a semicircular bifurcated portion 13. In this bifurcated portion 13 and pivot- 45 ally secured to the arm proper is an arm 14, to which the recording mechanism 15 is suspended. The recording mechanism 15 consists of a bracket 16, having a plurality of downwardly-projecting ears 17, onto which 50 the yoke 18 is hingedly connected by means of the bolt 19. This hinge connection is accomplished by means of the ears 20, formed on the yoke 18, provided with suitable openings which communicate with like openings 55 formed in the ears 17, through all of which the bolt 19 is passed, and on said bolt between

the ears are located springs 21, the purpose of which is to retain the yoke in alinement with the bracket 16 and to hold the same in a rigid position. Between the downwardly-projecting arms 22 of the yoke 18 is pivotally mounted a recording-wheel 23, having preferably four type-faces 24, which are provided with dovetail grooves 25, in which type 26 of similar form is inserted, which type is to indicate the name of train number and initial of the car. On the pivot on each side of the wheel is provided a ratchet 27, against which comes in contact a retaining-spring 28, one end of which is rigidly secured to the upper portion 60 or horizontal member of the yoke, and its free end bearing against the surface of said ratchet for retaining the wheel in position that the type might accurately print when brought in contact with the register, the operation of 65 which will be hereinafter fully described. Upon the horizontal member of the yoke 18 are also mounted arms 29, on the end of which are provided brushes 30, with which come in contact the type 26 during the revolution of 70 the wheel 23, which is for the purpose of 75 cleansing said type and free it from any foreign substance.

On the bolt 19 is supported a type-protecting arm 31, said arm being loosely mounted 80 upon said bolt and is for the purpose of protecting the type from coming in contact with the register or printing while the car is being backed or switched. The ears 17 are provided with a square shoulder 32, against 85 which the horizontal member of the yoke comes in contact and prevents the same from swinging in the direction indicated by the arrow *a* in Fig. 9. The loose mounting of the type-protecting arm 31 will permit the 90 same to swing in the direction indicated by the arrow *c* in Fig. 9 when the end 33 comes in contact with any obstacle which might be located on the road-bed.

The lower ends of the arms 22 are provided 95 with projections 34, which are designed to come in contact with and operate the dog 35, pivotally located upon the register-mechanism-operating lever 36.

The register previously mentioned is located on the road-bed in a convenient position and in alinement with the recording mechanism 15, and said register consists of a base-plate 37, provided with two vertical walls 38 and 39. Between the vertical walls 110 38 and 39 are located the recording-tapes mounted upon rollers 40, the projecting ends

thereof located in slots 41. The recording-tape 42 is passed over a resilient roller 43, its shaft 44 being mounted in the journal-boxes 45, which boxes are spring-actuated and guided in the slot 46, formed in each of the walls. This is for the purpose of permitting the type to make an impression upon the tape 42 and provide sufficient elasticity to prevent the same from cutting. The tape 42 passes between two rollers 47. On one end of the lower roller is provided a pinion 48, which meshes with a gear-wheel 49 mounted upon a shaft 50 and operates a roller 51, located between the walls 38 and 39 and has bearing in the slots 52. To the roller 51 is attached an ink-ribbon 53, guided over a pin 54, passing over the tape 42 and roller 43 and attached to a roller 55, located in the opposite end of the register and has bearing in slots 56.

One end of the lever 36 is provided with a spring-actuated pawl 57, engaging with the tape of the gear-wheel 49 to revolve the same when the projections 34 of the arms 22 come in contact with the spring-actuated dog 35. The lever 36 is held in normal position by means of the spring 58, and the pinion 48 is prevented from operating in reverse direction by means of the dog 59. The entire operating mechanism of the register is covered by a housing 60, which has a recess 61, formed in its top immediately above the roller 43, the surface of said register being curved, and the portion forming the two sides of the opening are suitably bent upwardly to form the projections 62, between which come in contact the type of the recording mechanism and register through the ink-ribbon onto the tape 42. The upper surface 35 of the housing is also provided with a pair of guides 63, with which come in contact the arms 22 of the recording mechanism and shift the register sideways should any ease of irregularity of the rails or trucks bring the recording mechanism out of proper alignment with the register. This shifting feature of the register is permitted by means of the shaft 64 passing through the ears 65, formed on the base of the register and supported in 40 the brackets 66, located upon the ties of the road-bed.

An operating-shaft 67 is located upon one of the ties and provided with cams 68, which when said shaft is operated by means of the handle 69 the cam 68 will come in contact with the lower surface of the register and raise the front end of the register horizontally with the rear, which operation is necessary to cause the recording mechanism to print. The purpose of raising and lowering the register by means of the cams 68 is to provide an additional safeguard against the recording mechanism coming in contact with the register while switching. The recess 61 55 of the register is closed by a cover 70, suit-

ably hinged to the housing, and is automatically opened and closed by means of the lever 71, the rod 72, bell-crank 73, and cord 74, operated by the shaft 67 and closed by means of a spring 70 when the lever 71 is lowered. 70 The cover 70 is to remain closed while the register is in an inclined or lowered position, and immediately upon raising the register by the handle 69 the cover is simultaneously opened with the raising of the register coming in contact with the spring 70 depressing the same. 75

If it is desired at any time to replace or remove the type in the recording mechanism, the pin 75 is removed, and the entire mechanism can be swung around on the pivot 76 in alinement with the arm 12, thus bringing the entire mechanism on the side of the car conveniently to be repaired. The spring-actuated dog 35 operates through a slot 77, 80 formed in the housing of the register, and will only operate the lever 36 when the recording mechanism strikes it in the direction indicated by the arrow e. (See Fig. 4.) Should by accident an obstacle strike the dog 35 90 from the opposite direction, it will cause the same to move downwardly upon its pivot without operating the arm 36 and immediately on being released will be replaced to its normal position by means of a spring 78. 95

Having thus described my invention, what I claim as new, and desire to have secured to me by the grant of Letters Patent, is—

1. A device of the class described, comprising a recorder, a recording mechanism, a mechanism for tilting the recorder to place it in alinement with the recording mechanism, a tape located in the recorder, a mechanism for moving the tape step by step, a recording-ribbon located in the recorder and communicating with the tape, a cover located on the recorder, a mechanism for automatically operating said cover to open and close the opening through which the record is made, substantially as specified. 100

2. A device of the class described, comprising a recorder, a recording mechanism carried by the car, a recording-wheel provided with type indicating the number and initial of the car, brushes carried by the recording mechanism with which the type come in contact for cleansing the same, a type-protecting arm carried by the recording mechanism for protecting the type, a recorder mechanism for operating tapes located in the recorder, a spring-actuated dog located upon the recorder mechanism for operating the same when brought in contact with the recording mechanism, and a suitable mechanism for tilting the recorder to bring it in 110 alinement with the recording mechanism, substantially as specified. 115

3. A car-recorder, comprising a suitable casing located upon the railway road-bed, means whereby lateral motion may be im- 120 125 130

parted to the casing, an actuating mechanism whereby the casing may be tilted, a tape and recording-ribbon located within the casing, an actuating mechanism for operating the tape and ribbon step by step, a recording mechanism carried by the car, guides formed on the casing to guide the recording mechanism and operate the tape-actuating mechanism, a cover located on the casing automatically opened and closed with the raising and lowering of the recorder for opening and clos-

ing the recess through which the record is made by the recording mechanism, substantially as specified.

In testimony whereof I have signed my name to this specification in presence of two subscribing witnesses:

FREDERICK A. SCHIERBERG
